United States Patent

Des. 237,159
Patented Oct. 14, 1975

237,159

ROADWAY MARKER

Howard A. Schaefer, Lancaster, Ohio, assignor to
Anchor Hocking Corporation

Filed Sept. 9, 1974, Ser. No. 504,326

Term of patent 14 years

Int. Cl. D10—06

U.S. Cl. D10—113

FIG. 1 is a top plan view of a roadway marker showing my new design;

FIGS. 2-3 are front and side elevation views, respectively, of the roadway marker shown in FIG. 1;

FIG. 4 is a bottom plan view of the roadway marker shown in FIGS. 1-3; and

FIG. 5 is a cross-sectional view in elevation taken through FIG. 1 along the line 5—5.

I claim:

The ornamental design for a roadway marker, substantially as shown and described.
